UNITED STATES PATENT OFFICE.

JOHN H. BRUNINGA AND EDWARD P. EVERE, OF ST. LOUIS, MISSOURI, ASSIGNEES TO
HENRY HYMAN, OF NEW YORK, N. Y.

BATTERY HAND LAMP.

Application filed February 12, 1926. Serial No. 87,858.

This invention pertains to battery hand lamps and more particularly to that type of lamp in which a plurality of lamps are mounted in a single reflector arranged to 5 be lighted selectively at the will of the operator.

In the construction of a hand lamp of this type it is practically necessary to provide an enlarged head since the ordinary casing for 10 receiving the battery has become more or less standardized in its transverse dimension. Furthermore, the head should be made removable so as to facilitate the insertion and removal of the reflector and to render more 15 convenient the details of manufacture and repair. Since only one of the lamps can be placed in the center of the casing, the others must be displaced therefrom and must, therefore, be definitely positioned in order that 20 current from the battery may be properly carried thereto. Accordingly, the problem of definitely positioning the reflectors in the head so as to properly engage the lamps with the connections to the battery presents some 25 difficulty.

One of the objects of this invention is to provide a construction in which the reflector and its extra lamps may be definitely positioned with respect to the casing.

Another object is to provide simple means for fixing the position of the reflector and to prevent rotation thereof during manipulation of the head and fittings.

Further objects will appear from the following description taken in connection with the accompanying drawing, in which:

Figure 1 is a longitudinal section of a battery hand lamp embodying this invention.

Figure 2 is a similar section of part of the lamp taken at right angles to the section of Figure 1.

Figure 3 is a side view of the multiple switch.

Figure 4 is a plan view of the reflector support, and

Figure 5 is a top view of the complete lamp.

Referring to the drawing, 1 designates a casing for receiving the battery. This may 50 be constructed of any suitable material in a manner well known to those skilled in the art and may be provided with a base cap 2 having a spring 3 for contacting with the battery in the usual manner.

An enlarged head 4 may be provided for

attachment to the casing by means of a threaded fitting 5 or any suitable means well known in the art. A reflector 6 fitting the head 4 is provided with a central lamp socket 7 and one or more side sockets 8 in 60 all of which lamps 9, of the usual type may be mounted.

The reflector is supported in the head 4 by means of an insulating support 10 in the form of a ring of fibre or other suitable 65 material which may, if desired, be reinforced by a cup or flanged rim 11. This support is adapted to seat upon a flange 12 in the head 4. The support is provided with a central opening 13 adapted to fit the 70 reflector 6 and side notches 14 adapted to receive the sockets 8 so as to position the same in the head. Another notch 15 is provided to receive a positioning element as will presently be described so as to position 75 the support itself. This support serves to insulate the reflector from the head 4. This reflector may be further insulated at its upper rim by an insulating ring 16 and is held in place by the usual lens or glass cover 17 80 and the clamping rim 18.

On the side of the casing 1, is mounted a multiple switch 19, as illustrated in Figures 2 and 3. This switch may be of any suitable construction well known in the 85 art and comprises three separate switches mounted in a single housing. A connecting strip 20 connects this switch with the lower cap 2 and with the battery. From the upper contacts 21 of the separate switches, separate 90 connections pass upwardly along the inside of the casing to carry current to the lamps. A strip 22 passes upwardly from the central switch and is bent over so as to engage the lamp in the center socket 7. Similarly side 95 strips 23 suitably offset to diametrically opposite points in the casing pass upwardly in the head 4 extending through the notches 14 in the support and adapted to engage lamps in the sockets 8 as illustrated in Figure 1. A strip 24, which is preferably of a 100 comparatively heavy material so as to be stiff, contacts with the central terminal of the battery as shown in Figure 2 and extends upwardly through the notch 15 in the support 10 and contacts with the reflector so as to connect said reflector in the battery circuit. This strip is firmly secured by rivets or other suitable fasteners 25 to the casing and by its engagement with the 110

notch 15 anchors the support 10 against rotation in the head. With the support so anchored alinement with the sockets 8 with the strips 23 is fixed so that lamps in these 5 sockets will always make contact with those strips.

In the use of this hand lamp, bulbs 9 of different colors are mounted in the different sockets. For instance, the central bulb may 10 be clear white and the other two red and green respectively. The device may then be used by switchmen and the like for signaling process by lighting the lamps of appropriate color as desired.

15 It will be noted that this invention provides a simple and inexpensive construction for a multiple bulb lamp of this type in which the reflector is not only adequately supported but is fixed in position so as to 20 insure proper alinement of the lamp socket. It is also secured against movement which will dearrange such alinement. The reflector may be removed at any time and must 25 always be inserted in a properly alined position. The same elements which serve to carry current to the various parts also serve to fix the alinement of the support and the reflector.

It is obvious that various changes may be 30 made in the details of construction, within the scope of the appended claims, without departing from the spirit of this invention; it is, therefore, to be understood that this 35 invention is not to be limited to the specific details shown and described.

Having thus described the invention, what is claimed is:

1. A battery hand lamp, comprising, a 40 battery-receiving casing, a head thereon, an insulating ring having a notch seated in said head, a reflector having a plurality of lamp sockets thereon seated in said ring with a 45 socket in the notch thereof, a plurality of switches on said casing, connections from said switches adapted to engage lamps in said sockets, and means cooperating with said insulating ring adapted to aline said sockets with said connections.

2. A battery hand lamp, comprising, a 50 battery-receiving casing, a head thereon, a reflector having a plurality of lamp sockets

thereon, a plurality of switches on said casing, connections from said switches adapted to engage lamps in said sockets, and an insulating support for said reflector seated 55 in said head and having recesses therein adapted to receive certain of said sockets and certain of said connections, whereby said sockets are alined with said connections and said support is anchored in said head. 60

3. A battery hand lamp, comprising a battery-receiving casing, a head removably mounted on one end thereof, an insulating support seated in said head and having a notch, a reflector provided with a plurality 65 of lamp sockets and seated in said support with one of said sockets engaging said notch, means for connecting said reflector in the battery circuit, and a plurality of switches on said casing adapted for lighting lamps in 70 said sockets.

4. A battery hand lamp, comprising, a battery-receiving casing, a head removably mounted on one end thereof, an insulating support seated in said head and having a 75 notch, a reflector provided with a plurality of lamp sockets and seated in said support with one of said sockets engaging said notch, a connector in the battery circuit extending into said notch and adapted to engage a 80 lamp in said one socket, means for connecting said reflector in the battery circuit, and a plurality of switches on said casing adapted for lighting lamps in said sockets.

5. A battery hand lamp, comprising, a 85 battery-receiving casing, a head removably mounted on one end thereof, an insulating support seated in said head and having a plurality of notches, a reflector provided 90 with a plurality of lamp sockets and seated in said support with one of said sockets engaging one of said notches, a connector fixed to said casing and extending into another of said notches adapted to connect said reflector in the battery circuit, and a plurality of 95 switches on said casing adapted for lighting lamps in said sockets.

In testimony whereof we affix our signatures this 5th day of January, 1926.

JOHN H. BRUNINGA.
EDWARD P. EVERE.
